Primary Examiner — Eliza Z Harvey*Assistant Examiner* — Kayla Marie Bennett(74) *Attorney, Agent, or Firm* — Lerner David LLP(57) **CLAIM**

The ornamental design for a template for deck boards, as shown and described.

DESCRIPTION

This application is related to application Ser. No. 29/795,504, entitled TEMPLATE FOR DECK BOARDS, and concurrently filed herewith on Jun. 18, 2021, the disclosure of which is incorporated herein by reference.

FIG. 1 is a front perspective view of a template for deck boards showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof showing the template for deck boards in an environment of use.

The broken lines of even length in FIG. 8 represent environmental features that form no part of the claimed design.

1 Claim, 5 Drawing Sheets(56)
